UNITED STATES PATENT OFFICE.

JOHN W. STATON, OF EL RENO, OKLAHOMA, ASSIGNOR OF ONE-HALF TO GEORGE B. SAVAGE, OF HOLLIS, OKLAHOMA.

RAIL JOINT.

Application filed May 13, 1927. Serial No. 191,199.

This invention relates to railroad construction and more particularly to the joint formed between the rails, whereby the rail ends are maintained in alinement and braced vertically and laterally and the nuts of the fish plate connecting bolts are secured against loosening.

The invention provides a joint including a plate which is secured to the tie or foundation and underlaps the rail ends, said plate having a flange to overlap the base of the rails and an upstanding portion to extend along a side of the rails and cut away to receive the nuts, and having a retaining flange to engage a confining plate which overlaps the opposite side of the base of the rails, both plates being spiked or otherwise secured to the tie or other foundation of the road bed.

While the drawing illustrates a preferred embodiment of the invention, it is to be understood that in adapting the means to meet specific needs and requirements, the design may be varied and such other changes in the minor details of construction may be resorted to within the scope of the invention as claimed without departing from the spirit thereof.

For a full understanding of the invention and the merits thereof, reference is to be had to the following description and the accompanying drawing, in which,—

Figure 1 is a top plan view of a rail joint embodying the invention.

Figure 2 is a side view thereof.

Figure 3 is a vertical, transverse sectional view on the line 3—3 of Figure 1, looking in the direction of the arrows.

Corresponding and like parts are referred to in the following description and designated in the several views of the drawing by like reference characters.

The numeral 1 designates contiguous ends of adjacent rails and 2 the tie or other foundation to which the rails are secured. The tie plate 3 is adapted to be spiked or otherwise secured to the foundation and is of a length to extend beneath the joint and upon opposite sides thereof for a determinate

distance. The plate 3 is provided adjacent 50 one end with a flange 4 which is adapted to overlap a side portion of the base of the rails and is formed with an upstanding portion 5 which extends along a side of the rails and which is cut away, as indicated at 6, to receive the nuts 7 applied to the threaded ends of the bolts 8 which connect the fish plates 9 to opposite sides of the rails. A retaining flange 10 is formed at the opposite end of the plate 3 and receives the outer marginal 60 portion of a confining plate 11 which overlaps the adjacent side of the base of the rails. A brace 12 connects the upstanding portion 5 with the overhanging flange 4 and a similar brace 13 extends upwardly from the confining plate 11 and engages the side of the adjacent fish plate 9. The vertical edge of the brace 13 is cut away, as indicated at 65 14, to clear the head of the bolt 8, this being necessary because the plate 11 is placed in 70 position and removed by an endwise movement. The end portion of the plate 3 provided with the overhanging flange 4 is formed with openings 15 which receive the spikes or other fastenings employed for securing the plate to the tie or foundation 2. The opposite end portion of the plate 3 is formed with elongated openings 16 which are adapted to register with openings formed in the confining plate 11. The openings 16 75 are elongated in a direction lengthwise of the plate to admit of lateral movement of the confining plate 11 so that it may engage the adjacent side of the joint. The type of fastenings employed for securing the plates 3 and 11 to the rail support will depend upon the nature of the tie or foundation, as will be readily understood.

Having thus described the invention, I claim:

In a rail joint, the combination with the rail ends, fish plates upon opposite sides of the web portion of the rail ends, and connecting bolts passing through the fish plates and webs of the rail ends, of a tie plate 90 underlapping the rail ends and projecting from opposite sides thereof, and having a confining flange at one end and a flange ad-

5 jacent the opposite end to overlap the side portion of the base of the rail ends and terminating in an upstanding portion having portions cut away to receive the nuts of the fish plate connecting bolts, and a confining plate having its outer marginal portion engaged under the said retaining flange and

overlapping the adjacent side portion of the base of the rail ends and having a brace engaging the side of the joint opposite that 10 engaged by the upstanding portion of the tie plate.

In testimony whereof I affix my signature.
JOHN W. STATON. [L. s.]
